(57) **CLAIM**

The ornamental design for a glove as shown and described.

DESCRIPTION

FIG. 1 is a front view of a glove.

FIG. 2 is a back view of the glove of FIG. 1.

FIG. 3 is a right side view of the glove of FIG. 1.

FIG. 4 is a left side view of the glove of FIG. 1.

FIG. 5 is a top plan view of the glove of FIG. 1; and,
FIG. 6 is a bottom plan view of the glove of FIG. 1.

The dash-dash broken lines in the figures depict portions of
the article and form no part of the claimed design. The
dash-dot broken lines in the figures show boundaries of the
claimed design and form no part thereof.

1 Claim, 6 Drawing Sheets
